UNITED STATES PATENT OFFICE

2,350,995

THREAD TENSION FOR SEWING MACHINES

Fred Ashworth, Wenham, Mass., assignor to
United Shoe Machinery Corporation, Flemington,
N. J., a corporation of New Jersey

Application October 5, 1942, Serial No. 460,743

10 Claims. (Cl. 112—59)

The present invention relates to improvements in thread tensioning devices for use in sewing machines operating on shoes or other heavy materials of the type employing a hook needle and a take-up acting to take up each loop of thread drawn through the work by the needle and to give up thread during each sewing cycle at a rate greater than required by the other stitch forming devices, so that the portion of thread engaging the take-up becomes slack during a part of each sewing cycle. An example of a machine of this type is disclosed in U. S. Letters Patent No. 2,271,611 of February 3, 1942, of which the present inventor is a joint patentee.

In the machine of the patent, a thread tensioning device is provided, acting on the thread between the take-up and the point of operation of the needle in the work, to keep those portions of the thread engaging the stitch forming devices other than the take-up under control while the take-up is giving up thread to said other stitch forming devices. In order to avoid the effects of excessive friction and abrasion on the thread while the take-up is taking up thread and particularly while a stitch is being set, mechanism driven from the main sewing shaft of the machine also is provided for actuating the tension to relieve the frictional effect of the tensioning device on the thread at certain times in each sewing cycle.

This invention has for an object to provide in a shoe sewing machine, means for controlling the tension on a sewing thread without the use of any actuating mechanism separate from the tensioning device. Other more general objects are to simplify and improve the construction of a lockstitch shoe sewing machine in such a way that it will operate not only more effectively and at higher speeds than heretofore, but will enable the machine to be threaded more easily and will avoid to a large extent incidental results of wear on the operating machine parts.

While certain features of the invention contributing to the attainment of the above objects are particularly applicable to shoe sewing machines having a rotary type take-up, in many respects the present invention is useful also in sewing machines having a take-up of any other type in which transverse as well as lengthwise movement is imparted to the thread during sewing. Broadly considered, the invention is embodied in a sewing machine having a hook needle, and any form of take-up with which a variable tensioning device is provided, the action of which device is controlled by transverse movement of the thread to change the degree of tension in the

thread. A particularly effective construction and arrangement is in a machine having a rotary take-up, the take-up stroke of which imparts a movement transverse to the thread length in one direction and the give-up stroke of which imparts a transverse movement to the thread in the opposite direction. In its preferred form, the tensioning device consists of a friction plate and a cooperating thread engaging block having surfaces arranged within the plane of rotation of the take-up and of said transverse thread movement and yielding means acting at one end of the plate nearest which the thread passes during the give-up stroke of the take-up to cause maximum tension to be applied to the thread during the give-up stroke. When the thread passes along the surfaces towards the other end of the plate, the effect of the yielding means is continuously reduced until a position is reached where little or no tension is imparted to the thread. Thus, in a sewing machine of the lockstitch type, little or no resistance is offered to movement of the thread about a shuttle or loop taker after the loop of needle thread engaging the loop taker has been enlarged to its maximum size and the take-up has begun to take up the loop. In this way, a particularly effective construction of tensioning device is provided in which no actuating mechanism therefor driven by the sewing shaft is required and with the use of which the same or improved results are obtainable as compared to those in prior machines of the class disclosed in the patent above referred to.

Other features of the invention reside in a novel and improved tensioning device through which the thread may readily be introduced when the machine is being threaded, as a preliminary to placing the machine in operation and in other devices, combinations and arrangements of parts hereinafter described and claimed, the advantages of which will be obvious from the following description taken in connection with the accompanying drawing illustrating one embodiment of the invention.

In the drawing,
Fig. 1 is a side sectional view looking from the left of the lower forward portion of a lockstitch shoe sewing machine embodying the features of the present invention, parts having been removed and a side cover plate for the rotary take-up having been swung open to expose the take-up during its give-up stroke at a position just before the thread becomes slack, indicated in broken lines, as a result of giving up needle thread at a rate

greater than required by the other stitch forming devices;

Fig. 2 is a similar view of the same parts indicating the take-up during its take-up stroke; and

Fig. 3 is a sectional plan view on an enlarged scale of the tensioning device indicating the position of the needle thread during the give-up stroke of the take-up.

The machine illustrated in the drawing is a lockstitch shoe outsole sewing machine having a curved hook needle 2, a continuously rotating take-up 4, a looper 6, a thread finger 8, a shuttle 10 containing a supply of locking thread and other stitch forming devices similar in construction and in mode of operation, except as hereinabove pointed out, to those disclosed in the patent above referred to. As in the machine of the patent, the stitch forming devices are so operated that substantially no tension will be imparted to the needle thread in each sewing cycle except when a stitch is being set. To control the needle thread while each loop is being formed and carried about the thread case in that machine, a frictional thread tensioning device is provided between the take-up and the work so that sufficient tension will be applied to the thread between the time the needle is looped and drawn through the work and the time the needle loop reaches a position of maximum extension about the thread case. The tensioning device both assists the needle looping operation and prevents displacement of the thread from the hook of the needle as the threaded needle moves upwardly through the work.

In order to reduce abrasion of the thread during the take-up stroke of the take-up, in the patented machine, the tension device is actuated with two degrees of pressure, the lighter pressure being effective during the take-up stroke of the take-up. The mechanism in the patented machine for changing the degree of pressure is actuated by connections driven from the main sewing shaft connected with a shaft corresponding to the shaft 12 on which the take-up 4 is mounted. This mechanism is subject to wear and requires accurate adjustment to perform its operation effectively, thus adding to the duties of the operator and to the expense of maintaining the machine.

The machine embodying the present invention is equipped with a frictional needle thread tensioning device located to act on the needle thread between the take-up and the work illustrated in the drawing as a shoe sole 13. This tensioning device causes the needle thread to be controlled in an advantageous manner without the use of any actuating mechanism separate from the tensioning device. Not only does the device thus require infrequent adjustment, but when it is necessary to replace any of the parts due to wear, a simple and easily accomplished interchange may be made without requiring disconnection of any other operating parts in the machine or the exercise of special precautions in reassembling replaced parts.

The construction of the improved needle thread tensioning device is illustrated best in Fig. 3 and comprises a block 14 secured to the frame of the machine and a cooperating friction plate 16. One side of the block 14 is formed with a thread engaging surface 18 along which needle thread extending between the looper and the take-up moves. The thread engaging surface 18 lies substantially in a plane defined by the circular path of a roll 20 on the arm of the take-up 4 so that as

the take-up roll moves about the take-up shaft 12 as a center in the direction of the arrow, the needle thread, indicated at 22, will move first along the surface 18 towards the rear of the machine before the take-up stroke of the take-up, as shown in Fig. 2, and towards the front of the machine before the give-up stroke of the take-up, as shown in Fig. 1. To impart a frictional effort on the thread, the thread 22 is compressed yielding by the plate 16 secured to a stud 24 passing loosely through an opening in the block 14 at right angles to the thread engaging surface thereon. Surrounding the stud 24 is a coil spring 26 acting against the side of the block 14 and an adjusting nut 28 threaded on the stud.

The arrangement of the stud and plate is such that during the give-up stroke of the take-up (Fig. 1) the thread will be drawn nearer the stud than during the take-up stroke of the take-up (Fig. 2). When the take-up has reached the position of Fig. 1, it gives up thread more rapidly than required by the other stitch taking devices. After reaching the broken line position of this figure, the thread engaging the roll 20 becomes relatively slack, and except for the tension imparted by the block 14 and plate 16, the thread carried by the needle would be out of control. At this point in the sewing cycle, the needle has just received the thread within its hook so that without tension the thread would be likely to become dislodged from the needle before the needle is withdrawn from the work. As the sewing cycle continues, the slack thread given up by the take-up is drawn about the thread case by the shuttle, and the take-up in rotating from the broken line position of Fig. 1 to the position of Fig. 2, moves the thread rearwardly along the thread engaging surfaces of the block and plate to a position at a distance from the stud 24. In this rearward position of the thread, there is little or no pressure of the plate against the thread, the plate acting as a lever with that end only nearer the stud engaging the block to form a fulcrum about which the plate swings slightly as the thread moves along the thread engaging surfaces. With the thread in the position of Figs. 1 and 3, nearly the full pressure of the spring 26 is exerted on the thread so that a much greater tension is imparted to the thread passing between the block and plate.

With the continuously rotating take-up referred to operating in a counterclockwise direction, as viewed in the drawing, a transverse movement of the thread is imparted in one direction towards the end of the give-up stroke of the take-up to reduce the tension on the thread, and a transverse movement in the opposite direction occurs towards the end of the take-up stroke to bring again the thread into maximum tensioning position. To limit the transverse movement of the thread on the thread engaging surfaces of the tensioning device, the frame of the machine forms a housing for the take-up and is constructed with a guide surface 30 and the block 14 carries a flanged guide wheel 32 rotatable on a shouldered screw 34 secured within the block at right angles to the plane of take-up rotation. The wheel 32 projects horizontally beyond the upper edge of the tension plate 16, thus preventing escape of the thread rearwardly from between the plate and block.

When introducing thread into the machine in preparation for a sewing operation, the plate 16 is moved clear of the guide wheel 32 and the stud 24 is made with sufficient length to obtain

the requisite movement. To hold the plate against rotation with the stud as a pivot, the forward end of the plate is slotted to receive a pin 36 carried by the block 14 in parallel relation to the stud.

Due to the pressure exerted on the thread when the thread is in its maximum frictional position nearest the stud 24, there is a tendency to strip lint from the thread and for the lint to collect around the stud. If this occurs, the friction plate 16 may be forced away from the block 14 so that improper tension will be imparted to the thread. To prevent accumulation of lint stripped from the thread from affecting the thread tension adversely, the block 14 is recessed at 38 to form a channel through which broken fiber ends of lint may drop from between the plate and block.

By the construction of a tensioning device thus described, the degree of friction imparted to the thread varies automatically between two limits as the transverse position of the thread changes along the thread engaging surfaces of the block and plate. No power driven actuating mechanism for the tensioning plates and no special adjustments to insure proper timing of the actuating mechanism are required as in the machine disclosed in the patent. The only adjustment to be made is in the tension of the spring 26 and once this is set by rotation of the thumb nut 28, no further changes are needed.

The nature and scope of the invention having been indicated and a particular embodiment thereof having been specifically described, what is claimed is:

1. In a sewing machine having a hook needle and a take-up acting to take up and give up thread and to move the thread transversely of its length, a tensioning device constructed and arranged to impart a variable tension to the thread, variation of which is controlled by transverse movement of the thread between the take-up and the work.

2. In a shoe sewing machine having a hook needle and a take-up, the take-up stroke of which imparts transverse movement to the thread in one direction and the give-up stroke of which imparts transverse movement to the thread in the opposite direction, a tensioning device constructed and arranged to impart a variable tension to the thread, variation of which is controlled by the transverse movement of the thread between the take-up and the work to increase the tension when the thread is moved transversely in one direction and to reduce the tension when the thread is moved transversely in the opposite direction.

3. In a sewing machine having a hook needle and a take-up acting to take up and give up thread and to move the thread transversely of its length, a tensioning device between the take-up and the work including a block and a plate having cooperating thread-engaging surfaces between and along which the thread moves, and yielding means near one end of the plate for exerting a varying pressure through the plate on the thread as it moves along said surfaces in a direction transversely of the length of the thread.

4. A shoe sewing machine having, in combination, a hook needle, a take-up comprising a rotary member arranged to move in a circular path, a thread engaging member on the rotary member acting to take up and give up thread to the needle and to impart transverse movement to the thread between the take-up and give-up

strokes, and a tensioning device for the thread between the thread engaging member and the work including a friction plate and a cooperating thread engaging block having surfaces arranged within the plane of rotation of the thread engaging member to enable movement of the thread along said surfaces as the thread engaging member is actuated, and yielding means acting at one end of the plate nearest which the thread

passes while the thread is being given up to cause a greater tension to be applied to the thread while being given up than while being taken up by the take-up.

5. A shoe sewing machine having, in combination, a hook needle, a take-up comprising a rotary member arranged to move in a circular path, a thread engaging member on the rotary member acting to take up and give up thread to the needle and to impart transverse movement to the thread between the take-up and give-up strokes, and a tensioning device for the thread between the thread engaging member and the work including a friction plate and a cooperating thread engaging block having surfaces arranged within the plane of rotation of the thread engaging member to enable movement of the thread along the surfaces as the thread engaging member is actuated, a yielding actuated stud for securing the plate to the block at one end of the plate nearest which the thread passes while the thread is being given up to cause less friction to be applied to the thread while being taken up by the take-up than while being given up.

6. A shoe sewing machine having, in combination, a hook needle, a take-up comprising a rotary member arranged to move in a circular path, a thread engaging member on the rotary member acting to take up and give up thread to the needle and to impart transverse movement to the thread between the take-up and give-up strokes, and a tensioning device for the thread between the thread engaging member and the work including a friction plate and a cooperating thread engaging block having surfaces arranged within the plane of rotation of the thread engaging member to enable movement of the thread along the plate during actuation of the take-up, a stud loosely supported by the block secured to one end of the plate nearest which the thread passes while being given up by the take-up, and yielding means acting on the stud to impart greater friction to the thread when located nearer the stud than when passing between the plate and block at a greater distance from the stud.

7. A shoe sewing machine having, in combination, a hook needle, a take-up comprising a rotary member arranged to move in a circular path, a thread engaging member on the rotary member acting to take up and give up thread to the needle and to impart transverse movement to the thread between the take-up and give-up strokes, and a tensioning device for the thread between the thread engaging member and the work including a friction plate and a cooperating thread engaging block having surfaces arranged within the plane of rotation of the thread engaging member to enable transverse movement of the thread along the plate during actuation of the take-up, yielding means acting at one end of the plate located at a position to impart greater friction to the thread while being given up than while being taken up by the take-up.

8. A shoe sewing machine having, in combination, a hook needle, a take-up comprising a rotary member arranged to move in a circular path, a thread engaging member on the rotary member acting to take up and give up thread to the needle and to impart transverse movement to the thread between the take-up and give-up

up, and a thread guide for limiting transverse movement of the thread while being taken up.

8. A shoe sewing machine having, in combination, a hook needle, a take-up comprising a rotary member arranged to move in a circular path, a thread engaging member on the rotary member acting to take up and give up thread to the needle and to impart transverse movement to the thread between the take-up and give-up strokes, and a tensioning device for the thread between the thread engaging member and the work including a friction plate and cooperating thread engaging block having surfaces arranged within the plane of rotation of the thread engaging member to enable transverse movement of the thread along the plate during actuation of the take-up, a stud for retaining the plate on the block, and means for preventing lint stripped from the thread from accumulating between the plate and block about the stud.

9. In a lockstitch shoe sewing machine having stitch forming devices including a needle, a shuttle and a take-up acting to take-up and give-up thread to the shuttle, the combination with a tensioning device comprising a thread

engaging block and a cooperating friction plate, a thread guide on the block for limiting transverse movement of the thread along the plate, and a spring-pressed stud secured to the plate passing through the block and being of sufficient length to enable the plate to be moved away from the block clear of the guide while applying thread to the tensioning device.

10. In a lockstitch shoe sewing machine having stitch forming devices including a needle, a shuttle and a take-up acting to take-up and give-up thread to the shuttle, the combination with a tensioning device comprising a thread engaging block and a cooperating friction plate, a thread guide on the block for limiting transverse movement of the thread along the plate, a spring-pressed stud secured to the plate passing through the block and being of sufficient length to enable the plate to be moved away from the block clear of the guide while applying thread to the tensioning device, and a pin mounted in parallel relation to the stud on the block for engaging the plate to prevent rotation of the plate with the stud as a pivot.

FRED ASHWORTH.
